COMBINATION SPOT AND FLOOD LIGHT

Theodore Hall, New York, N. Y., assignor to
Hall & Connolly, Inc., New York, N. Y., a corporation of New York

Application November 20, 1929, Serial No. 408,432

11 Claims. (Cl. 176—51)

This invention relates to searchlights, motion picture studio lights, or other reflector lights, which may be used interchangeably for spot or flood lights. Where only moderate beam spread is desired as in searchlights, it is the usual practice to move the light source toward the reflector from the focal point to spread the beam. Where a larger beam spread is desired, this method cannot be used as it is not practicable to bring the arcing face of the electrodes very close to the reflector. In such case I propose to move the light source away from the focal point so as to cross the beam at some point between the light source and the field to be illuminated. By my improved method, I also relatively move the light source or lamp and the reflector so that the lamp is positioned to one side of the optical axis of the reflector as it is moved away from the same and thereby avoid the casting of a large shadow by the lamp mechanism which would otherwise increase with the spread of the beam.

Referring to the drawings in which several forms of the invention are shown,

Fig. 1 is a vertical section through the searchlight or floodlight, most of the lamp mechanism, however, being shown in elevation.

Fig. 2 is a detailed view of a modified form of raising and lowering mechanism for the lamp.

Fig. 3 is a detail on an enlarged scale of a portion of Fig. 1.

Fig. 4 is a diagram showing how the beam is spread by backward movement of the lamp from the focal point.

Fig. 5 is a diagram showing how a shadow is avoided by my invention when a large beam spread is desired.

Fig. 6 shows a modified form of my invention in diagrammatic form.

Fig. 7 is a detail showing an automatic method of adjusting the mirror in the form of the invention shown in Fig. 6.

Fig. 8 is an enlarged detail of the chain catch shown in Fig. 1.

I have shown my invention as applied to a studio light having a reflector 1, housing or drum 2, and the arc lamp 3. The lamp is preferably of the high intensity type in which the crater or face 4 of the positive carbon 5 is the principal light source normally located at the focal point of the reflector to project a parallel beam. The positive electrode holder is provided with cooling ribs 6 and with rotating and feeding mechanism 7 and 8, all of which covers a sizable area and causes a small blind spot in the beam. The negative electrode 9 likewise has feeding mechanism

10. Both mechanisms are actuated from automatic means in the base 11 through telescoping universal shafts 12 and 13. Both electrode holders are mounted on a frame 14 which is supported on the top of control box 11.

In order to vary the spread of the beam, the entire lamp mechanism is adjustably mounted within the drum as by slidably mounting box 11 on hollow parallel shafts 12 extending longitudinally through the base of the drum. Each 10 of said shafts extends through lugs 13' and 14' projecting from opposite sides of the box. A stop collar 15 is secured to at least one of said shafts to stop the lamp mechanism when the arc has advanced to the focal position of the reflector. Adjustment of the lamp is secured by turning handle 16 on threaded shaft 17 which extends within shaft 12'. A toothed latch 17' secured to the top of box 11 extends through a slot 18 in shaft 12' and normally engages the 20 threads on shaft 17, but said latch may be disengaged for quick adjustment by pulling upwardly on finger piece 19.

As stated above, I prefer to provide a means for moving the lamp relatively downwardly with 25 respect to the beam axis at the time it is moved backwardly to spread the beam, the purpose being best explained by reference to Figs. 4, 5 and 6. If the lamp is moved rearwardly in the beam axis from its focal position 0, a fairly satisfactory 30 spread beam will be obtained if the spread is not very great as shown in Fig. 4, the beam crossing at C well behind the lamp mechanism. If, however, more spread is desired, the point of crossing moves up close to or intersects the lamp, 35 thereby casting a large shadow. By moving the lamp downwardly, however, as in Fig. 5 and by inclining the negative electrode 9 at a substantial angle, the lamp mechanism may be moved out of the reflected beam and a shadowless 40 spread beam obtained. Or, instead of shifting the lamp, the beam axis may be raised as by tilting upwardly the reflector as in Fig. 6 so as to 45 secure the same result.

One method of effecting the downward movement of the lamp is shown in Fig. 1. Journaled on the base 11 is a sprocket wheel 20 to which is secured a chain 21 which is detachably secured at its outer end to the front of the housing 2, as by catch 22. On the shaft of said sprocket is 50 secured a crank arm 23 (see also Fig. 3) pinned near its free end to upright link 24 which in turn is pivoted at its upper end to a lug 25 extending from frame 14 of the lamp. Said lug 25 has an aperture (not shown) through which a post 55

extends which rises from box 11 and may be braced by bracket 27. A similar apertured lug 25' extending from the bottom of frame 14 engages the lower end of the post. Small guide 5 posts 28 and lugs 29 may be provided at the other end of frame 14 to prevent swivelling.

From the foregoing, the operation of my invention should be apparent. When the lamp is at the focal point, it is against collar 15 and is 10 at the same time raised to and kept in position by sprocket wheel 20 and chain 21 through the linkage described. As the lamp is drawn rearwardly to spread the beam by turning crank 16, sprocket 20 moves toward the front of the drum, 15 slackening the chain, and thus allowing the lamp to descend slowly by gravity. As the lamp is thus moved, frame 14 will finally come to rest on top of box 11, in which position the shadow is avoided as in Fig. 5. Further movement will 20 only result in slackening the chain within changing the elevation of the lamp. Similarly in moving the lamp forwardly the elevating mechanism will not come into operation until the slack is taken out of the chain and the point at which 25 this occurs may be altered by changing the effective length of chain at catch 22. The amount of raising of the lamp may also be adjusted by changing the location of the pin connecting crank 23 and link 24 from hole 30 to hole 31 or otherwise. 30

The lamp may be locked in any desired vertical adjustment by turning the clamp screw 33 on a bracket 34 supporting sprocket 20 so as to prevent rotation of the sprocket wheel. At the 35 same time the chain should be disconnected at catch 22. This may be done as shown in Fig. 8 by raising the cover of the catch and lifting the chain 20 off lugs 22' on the base of the catch.

In Fig. 2 I show a modified means for raising 40 and lowering the lamp mechanism as it is moved back and forth. According to this form of the invention a cam 35 is mounted on the shaft 36 of the gear 37. Gear 37 meshes with a rack 38 which is moved back and forth with the lamp. 45 The cam may be shaped so as to elevate the lamp in steps if desired rather than in a gradual continual movement as the lamp is advanced to the focal point. Thus the cam is divided into a series of concentric steps 39, 40, 41 each raised above 50 the preceding step by an inclined portion 42.

Instead of lowering the lamp mechanism with respect to the axis of the beam, it is obvious that the beam may be relatively raised with respect to the lamp mechanism and the same advantages 55 secured. This may be conveniently accomplished by tilting the reflector rearwardly as shown in Figs. 6 and 7. The reflector is shown as hinged at 36' to the housing 2' so that it may be tilted backwardly within the limits of the slot 37' in 60 the link 38'. An annular housing 39' is shown to prevent the escape of light when the mirror is inclined, the catch 40' being provided to hold the mirror normally vertical. A mechanical connection to adjust the mirror in accordance with 65 the position of the lamp mechanism may be provided by running a cable or chain 39'' from the front of lamp box 11 around pulleys or sprocket wheels 42, 40'' and 41'' and to the back of the reflector 1'. As the lamp is moved rearwardly 70 to the focal point, therefore, the chain will draw the mirror into its upright position, where the beam axis coincides with the axis of the drum, while when the lamp is moved to the left to spread 75 the beam, the chain slackens and the reflector

becomes inclined under the action of gravity and/or of spring 43.

In accordance with the provisions of the patent statutes, I have herein described the principle and operation of my invention, together with the apparatus which I now consider to represent the best embodiment thereof, but I desire to have it understood that the apparatus shown is only illustrative and that the invention can be carried out by other means. Also, while it is designed to use the various features and elements 10 in the combination and relations described, some of these may be altered and others omitted without interfering with the more general results outlined, and the invention extends to such use. 15

Having described my invention, what I claim and desire to secure by Letters Patent is:

1. In a reflector arc light, a reflector, an arc lamp mechanism normally positioned with the arc at the focus of said reflector and the main 20 body of the mechanism on the opposite side of the arc from the reflector, means for adjusting the lamp away from the reflector to spread the beam, and means for automatically lowering said lamp as it is adjusted to minimize the shadow 25 from the lamp.

2. In a reflector arc light, a reflector, an arc lamp mechanism normally positioned with the arc at the focus of said reflector and the main body of the mechanism on the opposite side of the 30 arc from the reflector, means for adjusting the lamp away from the reflector to spread the beam, and means brought into action by said first-named means for simultaneously moving said lamp to one side of the optical axis of the reflector to minimize the shadow from the lamp. 35

3. In a reflector arc light, a reflector, an arc lamp mechanism normally positioned with the arc at the focus of said reflector when a parallel beam is desired, the main body of the mechanism 40 lying on the opposite side of the arc from the reflector, means for moving the lamp and focus away from each other to spread the beam, and means brought into action by such movement of the lamp for also adjusting the relative position 45 of the lamp and beam axis to place the lamp substantially without the spread beam.

4. In a reflector arc light, a reflector, a lamp and lamp mechanism normally positioned with the arc at the focus of said reflector when a parallel beam is desired, the main body of the mechanism 50 lying on the opposite side of the arc from the reflector, means for moving the lamp and focus away from each other to cross the beam between the lamp and the object illuminated, and means 55 for automatically, relatively lowering the lamp with respect to the beam axis to minimize the shadow from the lamp.

5. In a reflector arc light, a reflector, an arc lamp mechanism normally positioned with the arc at the focus of said reflector, means for adjusting the lamp away from the reflector to spread the beam, the main body of the mechanism lying on the opposite side of the arc from the reflector means for automatically lowering said lamp as it is adjusted to minimize the shadow 60 from the lamp, and means for locking the lamp at any desired elevation. 65

6. In a reflector arc light, a reflector, an arc lamp mechanism normally positioned with the arc 70 at the focus of said reflector when a parallel beam is desired, the main body of the mechanism lying on the opposite side of the arc from the reflector, means for moving the lamp away from said focus to spread the beam, and a connection 75

between said lamp and reflector for altering the position of the reflector to raise the beam above the lamp to avoid a shadow therefrom when the lamp is moved rearwardly to spread the beam.

5. 7. In a reflector arc light, a drum, a reflector, a lamp box, a pair of electrode holders, a common supporting frame for said holders mounted for raising and lowering on said box, means for slidably mounting said box within the drum whereby adjustment of the box along the axis of the reflector may be made, and a common means for sliding said box and raising and lowering said frame in a predetermined ratio.

8. In a reflector lamp, a reflector, an arc lamp mechanism having positive and negative electrode holders, the latter being inclined with respect to the former, means for adjusting the relative axial position of the arc and reflector to spread the beam, and a mechanical connection 15 between said first-named means and said lamp for adjusting such relative position laterally to place both electrode holders without the beam when spread.

9. In a high intensity reflector arc light, a drum, a reflector, a lamp box containing power means, a pair of electrode holders having feeding means for the electrodes and rotating means for one of said electrodes, telescopic driving connections for driving said feeding and rotating 25 means for said power means in said box, a sup-

porting frame for said holders vertically adjustable on said box, and means for adjusting the position of the box in the drum toward and away from the reflector and simultaneously raising and lowering said frame on said box in a predetermined ratio.

10. In a reflector arc light, a reflector, an arc lamp mechanism normally positioned with the arc at the focus of said reflector and the main body of the mechanism on the opposite side of the arc from the reflector when a parallel beam is desired, a common support for said reflector lamp and lamp mechanism means for pivoting the reflector on said support adjacent one edge thereof, and a common means for moving said lamp away from said focus and for tilting said reflector rearwardly on said pivot for the purpose specified.

11. In a reflector arc light, a reflector, an arc lamp mechanism normally positioned with the arc at the focus of said reflector, and the main body of the mechanism on the opposite side of the arc from the reflector, means for adjusting the lamp and reflector away from each other to spread the beam, and means operated by the 20 first-named means for lowering said lamp with respect to said reflector to minimize the shadow from the lamp.

THEODORE HALL.
